CLAIM

The ornamental design for a mount for a medical instrument, as shown and described.

DESCRIPTION

FIG. 1 is a perspective view of a mount for a medical instrument according to our new design;

FIG. 2 is a front elevation view of the mount for a medical instrument of FIG. 1;

FIG. 3 is a rear elevation view of the mount for a medical instrument of FIG. 1;

FIG. 4 is a top elevation view of the mount for a medical instrument of FIG. 1;

FIG. 5 is a bottom elevation view of the mount for a medical instrument of FIG. 1;

FIG. 6 is a right side elevation view of the mount for a medical instrument of FIG. 1; and,

FIG. 7 is a left side elevation view of the mount for a medical instrument of FIG. 1.

The broken lines depict parts of the mount for a medical instrument that form no part of the claimed design.
